PHONOGRAPH RECORD ENVELOPE

Samuel W. McCart, Washington, D. C.

Application April 5, 1948; Serial No. 19,115

1 Claim. (Cl. 206—62)

1

This invention relates to a record envelope. More particularly, the invention is concerned with an envelope for removably receiving a phonograph record, the envelope being adapted for movable disposition in an album, cabinet or other suitable container, whereby the record is protected when not in use and which can be readily withdrawn from the envelope without complete withdrawal of the envelope from the container.

Record envelopes for the above noted purpose are well known, and while the prior envelopes have been of diversified forms and capable of being retained in various kinds of containers or other receptacles, the more acceptable practice has been to support a plurality of the envelopes in a suitable receptacle and providing for individual tilting of the envelopes for removal of the records therefrom by means of a rod extending through the receptacle and aligned apertures in the envelopes.

In such an arrangement, a number of the envelopes are supported in the receptacle in pivotal support on the rod, such that when each envelope contains a record, the record space laterally will be filled, with the opposing sides of the envelopes in contact, whereby the envelopes will all remain in vertical position within the receptacle.

Generally, in these known arrangements, a holder or container of special design has been required and the envelopes cannot be used in an ordinary rectangular holder made of cardboard or similar material. In such an arrangement, however, when the holder contains only empty envelopes or when only a portion of the envelopes contain records, as most often will be the case, the lateral holder space is not filled; the envelopes, due to their relatively flimsy nature, will not stand erect, but will lop over toward one or both lateral walls, due to their own weight or their weight with that of any contained records, thereby making it necessary to straighten the envelopes to a vertical position each time it is desired to insert or to withdraw a record, thereby causing such great inconvenience and irritability as to make the arrangement useless. Furthermore, the leaning of any contained records toward the side walls promotes warping of the records.

It is accordingly a primary object of this invention to provide a record envelope whereby the above noted objections to existing envelopes are satisfactorily overcome.

A further object of the invention is to provide a record envelope for the above noted use whereby

2

a given number of envelopes may be supported in face-to-face contact within a receptacle, whether or not same are filled with records, and at all times be in a vertical position.

A still further and more specific object of the invention is to provide a record-supporting envelope including opposed side walls, to which a plurality of spacer blocks are secured, which blocks are substantially of a thickness equal to a record to be supported thereby, and with the blocks so disposed as to permit placing of a record in the envelope and removal therefrom, and so disposed that there are always at least two spacer blocks adjacent the front of the aligned envelopes. Other objects and advantages of the invention will become apparent in the course of the following detailed description, taken in connection with the accompanying drawings, wherein

Figure 1 is a plain view of the envelope prior to connection of the two sides thereof and showing a record in the position assumed thereby in the completed envelope.

Fig. 2 is an edge view of the partially completed envelope of Fig. 1 as viewed from the left thereof.

Fig. 3 is a side elevational view of the completed envelope and showing a record therein.

Fig. 4 is a horizontal sectional view in the plane of line 4—4 on Fig. 3.

Fig. 5 is a vertical sectional view of a container as viewed from above and in a plane parallel with its opposite side walls and showing envelopes therein, with one thereof moved forwardly for withdrawal of a contained record.

Referring now in detail to the drawings by use of reference characters, E designates the envelope in its entirety.

The envelope is preferably constructed of relatively heavy paper from which it is initially cut to the blank form shown in Fig. 1. This envelope blank comprises the opposing envelope side walls 10 and 11 adapted for folding on the dot-and-dash line a in bringing the side walls into parallel relation.

The wall portions 10 and 11 have aligning upper vertical edges 12 and lower aligning edges 13 which incline toward the bottom edge 14 of the envelope at the position of the fold line a, the portions 10 and 11 having aligning vertical edges 15 which provide the rear edge, while edges 12 and 13 are the forward edges.

The wall portion 10 is provided with a pair of front flaps 16 and 17 and a rear flap 18, which flaps, after folding side portion 11 about the line a into parallel relation with side portion 10, are bent upon the respective fold lines b, c and d

and lapped over the outer face of portion 11 and suitably adhesively secured thereto in the provision of the envelope as shown in Figs. 3 and 4.

The height of the envelope may be such that a record R projects slightly above the top mouth edge, but such edge preferably comprises a front horizontal portion 19 in the portions of the side walls of maximum height and a second horizontal portion 20 below the portion 19, whereby a substantial segment of the record is accessible 10 for grasping in removing same from or for placing same in the envelope.

Spacers 22 and 23 are suitably secured to a face of one or both of the side walls, and spacer 21 to the face of one side wall, here shown as 15 wall 10. These spacers are in the form of relatively thin blocks constructed of fiberboard or any other suitable relatively rigid material. The blocks 21 and 22 are disposed near the upper and lower front corners of the envelope and while 20 same may preferably be triangular, as shown, they may be of other forms. The block 23 is disposed adjacent the lower rear corner of the envelope, and while it may be various forms or sizes, it is preferably of substantial vertical dimensions, for the reason that the rear upper corner is not provided with a spacer.

These spacers are of a thickness substantially equal to that of the record R, and for different size records having different thicknesses, blocks of 30 corresponding thickness should be provided.

The spacer block 22 is provided with an aperture 24, and the side wall 11 and flap 17 are provided with apertures 25 and 26, respectively, which, in the assembled envelope, align with aperture 24 in the provision of the rod-receiving aperture 27, as indicated on Fig. 3.

The envelopes constructed as described are adapted for support in a suitable container C (Fig. 5), and a rod or other suitable pivot means 28 extends through the aligned apertures 27 in the envelopes.

As indicated in Fig. 5, the bottom edges 14 of the envelopes rest on the bottom wall 29 of the container, and the envelopes are individually tiltable forwardly about the corners 30 and around the rod 28 for removing a record from or placing same in an envelope. The rear portions of the top edges of the envelopes are preferably rounded, as at 31, whereby the space in the container above the envelopes may be restricted without interfering with the tilting of the envelopes.

Since the apertured spacer block 22 is aligned with the rod-receiving aperture 27, the envelopes are well guarded against the tear at this point. The spacer block 21 is beveled at 21' to facilitate withdrawal of the record R in avoiding catching of the record on an otherwise present shoulder on the block.

It will be observed from Fig. 1 that the envelope for any particular size record is of such dimensions that the record may have contact with the front, rear, and bottom edges of the envelope at the three points e, f, and g, whereby the record will be restrained in its plane within the envelope and will be retained out of contact with the spacer blocks 21, 22 and 23. Preferably, however, the record is of a slightly less diameter than the width of the envelope and may contact one or the other of the side edges upon slight movement in the direction of the short lines shown on Fig. 1. However, it will be observed that the record is

always in contact with the bottom edge of the envelope. The envelope will, in accordance with usual practice, be provided with identification tabs T.

With the use of the spacers as disclosed, the sides of the envelopes within the container will be maintained in contact at the front and rear edges whether or not records are in the envelopes, whereby the hitherto free space in the cabinet will not be present, and accordingly the envelopes will all remain in parallel vertical position without lopping over or becoming laterally inclined about the rod 28.

With the improved envelope, a record collector may provide a container having sufficient envelopes supported therein such that the container space will be filled when each envelope contains a record. He need not, however, be inconvenienced in a disarrangement of the envelopes, even though he has few or even no records in his possession, and he may then fill the envelopes at his leisure or as his financial ability may permit.

While I have disclosed my invention in accordance with a single specific embodiment thereof, such is to be considered as illustrative only, and not restrictive, the scope of the invention being defined in the following claim.

What I claim and desire to obtain by U. S. Letters Patent is:

A record envelope of generally rectangular form adapted for vertical disposition in use and including opposed side walls connected at the bottom and side edges and free at the top edge in the provision of a record admission and withdrawal mouth, a triangular spacer disposed in each of the upper and lower corners of the envelope at one edge thereof, and a spacer of substantial vertical extent disposed adjacent the lower corner of the envelope at the other edge thereof, the triangular spacer at the lower corner and the spacer of substantial vertical extent being disposed outwardly of a circle tangent to said bottom and side edges, and the triangular spacer at the upper corner being connected to one side wall and free of the other side wall for admission of a record to and withdrawal thereof from the envelope in the general plane thereof, one edge of the upper triangular spacer extending in angular relation to the top edge and adjacent side edge of the envelope in substantial spaced relation to the adjacent corner thereof, and said edge being bevelled to direct a record between said upper triangular spacer and said other side wall of the envelope upon withdrawal of the record from the envelope.
